UNITED STATES PATENT OFFICE

141,063

DESIGN FOR A SHIP'S LAMP

Peter Kiplock, Brooklyn, N. Y.

Application December 10, 1943, Serial No. 111,974

Term of patent 14 years

(Cl. D48—23)

To all whom it may concern:

Be it known that I, Peter Kiplock, a citizen of the United States, residing at Brooklyn, New York, county of Kings, and State of New York, have invented a new, original, and ornamental Design for a Ship's Lamp, of which the following is a specification, reference being had to the accompanying drawing, forming a part thereof.

Fig. 1 is a perspective view of a ship's lamp showing my new design, said lamp when viewed from the opposite side being substantially identical with Fig. 1.

Fig. 2 is a front view showing the interior of the lamp; and

Fig. 3 is a rear view of the lamp.

I claim:

The ornamental design for a ship's lamp, as shown and described.

PETER KIPLOCK.
